US0D1101814S

(12) **United States Design Patent** (10) **Patent No.:** **US D1,101,814 S**
(45) **Date of Patent:** **** Nov. 11, 2025**

(54) **DISPLAY SCREEN OR PORTION THEREOF WITH GRAPHICAL USER INTERFACE**

(71) Applicant: **GOOGLE LLC**, Mountain View, CA (US)

(72) Inventors: **Joseph Ball**, Brooklyn, NY (US); **Margaret Kae Banks**, Santa Cruz, CA (US); **Anja Lukovic**, Seattle, WA (US); **Courtney Lorraine Cox**, Seattle, WA (US); **Courtney Dattilo**, Boulder, CO (US)

(73) Assignee: **Google LLC**, Mountain View, CA (US)

(**) Term: **15 Years**

(21) Appl. No.: **29/932,641**

(22) Filed: **Mar. 14, 2024**

Related U.S. Application Data

(63) Continuation of application No. 29/913,709, filed on Oct. 6, 2023.

(57) **CLAIM**

The ornamental design for a display screen or portion thereof with graphical user interface, as shown and described.

DESCRIPTION

This application is related to U.S. patent application Ser. No. 29/913,606, filed Oct. 5, 2023, both of which are hereby incorporated by reference as if set forth herein in their entireties.

The drawing FIGURE is a front view of a display screen or portion thereof with graphical user interface showing our new design.

The outer broken line circle showing an electronic device, the inner broken line circle showing the display screen or portion thereof, and all other broken lines showing portions of the graphical user interface form no part of the claimed design.
